John Martino of Philadelphia, Penna. DES. 2093

assignor to

Stuart and Peterson, of the same place.

Letter Patent No. 2093-Dated June 13-1865

Ante-dated May 30-1865.

Design for the Plates of a Stove.

The schedule referred to in these letters Patent and making part of the same.

To all whom it may concern:

Be it known that I, John Martino, assignor to Stuart and Peterson of Philadelphia, County of Philadelphia, State of Pennsylvania, have invented or produced a new and original design for the plates of a cook stove, termed the "Barley Sheaf," and I do hereby by declare the accompanying drawing with the following explanation of the same to form a full, clear and exact description of the said design.

In the drawing.

Fig. 1. represents one of the side plates, and

Fig. 2. the front plate of the Barley Sheaf Cook Stove.

Round the edges of the side plate A, and at the upper and lower edges of the front plate B, is a plain beading a.

To the side plate are hinged the doors C and D, and above the latter is a panellet, which is edged with a plain beading b.

The door C has a plain oval beading d, round the inner and outer edges of which are the sprigs e, plainly shown in the drawing, the said beading enclosing a representation of barley sheaf f.

In the centre of the panel b, and also in the centre of the door D, is an oval beading d, at the inner edge of which are sprigs e, the said beading enclosing a monogram of the letters R.S. Near the lower side of the plate A, is an elongated panel g, with pointed ends, which is bordered by a plain beading h, and has in the centre an oval beading f.

To the front plate are hung two doors H, H, which are ornamented in the same manner as the door D on the side plate, and across the plate B, above the doors extend a ledge h, on which are a series of sprigs i. On the plate, at one side of each door H, is the ornament K of the character represented in fig. 2.

I claim

DES. 2093

The ornamental figures and forms, substantially as represented in and by the accompanying drawing, the whole forming an ornamental design for the side and front plates of the Barley Sheaf Cooking Stove.

In testimony whereof I have signed my name to this specification in the presence of two subscribing witnesses.
